CLAIM

The ornamental design for a fence post component as shown and described.

DESCRIPTION

FIG. 1 is a perspective view of a first embodiment of the fence post component showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment of the fence post component, showing my new design;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The drawings contain a symbolic break. The portion between the break lines forms no part of the claimed design.

1 Claim, 12 Drawing Sheets
